UNITED STATES PATENT OFFICE.

DAVID S. GRANT, OF METHUEN, MASSACHUSETTS.

PIPE-CUTTER.

SPECIFICATION forming part of Letters Patent No. 606,538, dated June 28, 1898.

Application filed February 7, 1898. Serial No. 669,325. (No model.)

To all whom it may concern:

Be it known that I, DAVID S. GRANT, a citizen of the United States, residing at Methuen, in the county of Essex and State of Massachusetts, have invented new and useful Improvements in Pipe-Cutters, of which the following is a specification.

This invention relates to improvements in pipe-cutters; and it consists of a frame having a hooked upper end, in bearings in which is journaled a hardened-steel cutter-disk combined with a longitudinally-adjustable and reversible cutter and roller carrying block having journaled in one end a pair of cutter-disks and in its opposite end a pair of rollers, said block being adjusted to and from the upper cutter-disk and the pipe to be cut by means of a screw-threaded shank, as will hereinafter be more fully shown and described, reference being had to the accompanying drawings, wherein—

Figure 1 represents a side elevation of my improved pipe-cutter, showing the carrying-block in its normal position relative to the frame—that is, with its rollers in operative position. Fig. 2 represents an edge view of Fig. 1. Fig. 3 represents a vertical section showing the position of the carrying-block reversed—that is, showing the cutter-disks thereon in operative position; and Fig. 4 represents a cross-section on the broken line 4-4, shown in Fig. 1.

Similar letters refer to similar parts wherever they occur on the different parts of the drawings.

In the drawings, A represents the frame of the device, having a hooked upper end A', in bearings in which is loosely journaled the hardened-steel cutter-disk B, as is common in devices of this kind.

On two opposite sides of the frame A are arranged guide-ribs A'' A'', on which the carrier-block C is guided to and from the cutter B by having angular extensions C' C' fitting against the rear portions of the guide-ribs A'' A'', as shown in Figs. 1 and 4.

The block C is detachably secured to a support D, preferably by means of a detachable pin d passing through the sides of the block C and a central projection on the said support D, as shown in the drawings.

E is the handle, secured to or made integral

with the shank E', which is guided in the lower tubular portion A³ of the frame A, as shown. The upper end e of said shank is 55 screw-threaded, as shown, and made to work in a nut F, preferably inserted in a recess in the upper part of the tubular portion A³, as shown in Figs. 1 and 3. The upper end of the screw e is connected in a suitable manner 60 to the part D, so as to cause the latter to be moved up and down during the rotary adjustment of the screw-threaded shank E' e, as is common in pipe-cutting devices.

In one end of the carrier-block C are journaled the cylindrical rollers G G, and in the opposite end of said carrier-block are journaled the hardened-steel cutter-disks H H, as shown.

In Figs. 1 and 2 the carrier-block C is shown 70 in position with its rollers G G facing the upper disk cutter B and causing the pipe I, that is being cut, to be confined between said upper cutter B and the rollers G G during the pipe-cutting operation. This is the usual 75 position of the carrier-block whenever there is room enough to swing the pipe-cutting device completely around the pipe that is being cut, and by using the tool in this manner a pipe may readily be cut off without causing 80 the edges at the cut to project outward, and consequently under ordinary conditions when the device may be swung freely in a complete revolution it is more advantageous to use the upper cutter B combined with the cylindrical 85 pressure-rolls G G; but when the device cannot be swung completely around—such as in corners of a room, &c., where the device has to be oscillated or rocked forward and back—it is preferable to use in connection with the 90 upper cutter B a pair of disk cutters H H, and for such purpose I reverse the position of the carrier-block C, so that the cutter-disks H H shall be held opposite to the upper cutter B during the pipe-cutting operation, as shown 95 in Fig. 3.

For the purpose of enabling the block C to be reversed from time to time as occasions may require I make on the ribs A'' A'' inclined cut-away portions or recesses a'' a'', adapted to allow the angular extensions C' C' to pass through such recesses when the block C is raised sufficiently to cause the lower projections C' to come opposite to the cut-away

- portions a'' a'' when the upper projections C' are liberated from the ribs A'' , and when the block C is in this position it may readily be swung outward and disconnected from the frame A , reversed, and connected to the latter in such reversed position. During the operation of removing the said block C from the frame A the pin d , which connects the said block to the support D , is withdrawn.
- 10 Having thus fully described the nature, construction, and operation of my invention, I wish to secure by Letters Patent and claim—
- 15 1. In a pipe-cutter, the combination with a frame having a disk cutter journaled in its upper end and provided on its opposite sides with longitudinal ribs having inclined slots or recesses formed intermediate their ends, of a reversible carrier-block longitudinally adjustable on said frame and having rollers in one end and cutter-disks in the other, said carrier-block being provided with hooked extensions arranged to engage the rear or outer faces of the ribs and adapted to be passed through the said slots or recesses therein to reverse the carrier-block, a support detachably connected to the carrier-block, and a screw-threaded shank working in a nut in the frame and swiveled in said support for adjusting the position of the reversible block to and from the upper cutter-disk, substantially as described.
- 20 2. In a pipe-cutter, the combination with a frame having a disk cutter journaled in its upper end and provided on its opposite sides with longitudinal ribs having inclined slots or recesses formed intermediate their ends, of a reversible carrier-block longitudinally adjustable on said frame and having rollers in one end and cutter-disks in the other, said carrier-block being provided with hooked extensions arranged to engage the rear or outer faces of the ribs and adapted to be passed through the said slots or recesses therein to reverse the carrier-block, and means for adjusting said reversible frame to and from the upper cutter-disk, substantially as described.
- 25

2. In a pipe-cutter, the combination with a frame having a disk cutter journaled in its upper end and provided on its opposite sides with longitudinal ribs having inclined slots or recesses formed intermediate their ends, of a reversible carrier-block longitudinally adjustable on said frame and having rollers in one end and cutter-disks in the other, said carrier-block being provided with hooked extensions arranged to engage the rear or outer faces of the ribs and adapted to be passed through the said slots or recesses therein to reverse the carrier-block, a support detachably connected to the carrier-block, and a screw-threaded shank working in a nut in the frame and swiveled in said support for adjusting the position of the reversible block to and from the upper cutter-disk, substantially as described.

In testimony whereof I have hereunto set my hand in presence of two subscribing witnesses.

DAVID S. GRANT.
